UNITED STATES PATENT OFFICE

2,345,392

BED DIVAN

Samuel L. Grossman, Los Angeles, Calif.

Application September 11, 1942, Serial No. 457,911

2 Claims. (Cl. 5—21)

This invention relates to bed divans, and it has as its main object to provide a practical and economical bed divan without the use of metal springs, hinges, levers and the like.

Inasmuch as metal is out for the duration of the war, and cannot be had for the purposes for which it has been used in the manufacture of bed divans, and other articles of furniture, it is an object of my invention to provide a bed divan which will give all of the usual conveniences and comforts of those in which metal springs, hinges, levers and the like are used.

Another object of my invention is to provide a bed divan in which the back thereof is fixed, or rigid, and cannot be let down to form a part of the bed when made down for sleeping purposes. This makes it unnecessary to pull it out from the wall in order to prepare it for sleeping purposes as a bed.

Another object of my invention is to provide a rigid carrier support for the cushions or mattresses, when made up as a divan, but which can be moved out to the front or bed position, with a flexible supporting member from the rear edge of said carrier support to a suitable support therefor in the rear portion of the structure, under the fixed back member, and which flexible supporting member collapses or folds up as said rigid carrier support is again pushed back into divan position.

Another object of my invention is to provide a double cushion or mattress structure, one upon the other, hingedly connected at their rearward adjacent corners with a fabric connection, whereby, when said carrier support is pulled out to the front, or bed position, with the double mattresses thereon, the top mattress can be turned back upon the extended flexible supporting member, to form a bed mattress, ready for use as a bed.

Another object of my invention is to provide a carrier support of the character referred to which can be moved on suitable wooden wheels, if desired, or moved like a drawer, from the divan position out to the bed position, and to provide means for holding said carrier support against moving backwardly when weight is placed upon the mattress supported by the flexible supporting member stretched thereunder by the movement of said carrier support to its front or bed position.

In order to fully explain my invention, I have shown on the accompanying sheet of drawings one practical embodiment thereof in which

Figure 1 is a vertical sectional view of a bed divan embodying my invention adjusted to the bed position, with parts shown in section;

Figure 2 is a similar view with the parts closed together in divan position;

Figure 3 is a sectional view taken on line 3—3 of Fig. 1, but showing the wheel or roller of the carrier support on its arched track and with the carrier frame free of the base members; and

Figure 4 is a horizontal sectional view taken on line 4—4 of Fig. 1, with parts broken out to reduce the size of the figure, and with other parts in plan view.

I will now describe in detail the embodiment of my invention as here shown for explanatory purposes.

My invention is shown in the form of a bed divan, having the base, or frame members, 5, 5, all secured rigidly together and forming a rectangular frame, with the feet 6, 6, at the four corners thereof, and with the rigid back structure 7, and the rigid arms 8, 8, at each end. As a part of the back structure, I provide at each end, frame members, as 9 and 10, the member 10 extending from one end to the other, and forming the support around which the covering 11, extending from the back up over the back structure and down in the front thereof and secured around said member 10, as indicated at 11 in the sectional views of Figs. 1 and 2.

This general construction and arrangement of the base, back and arm portions can be of any desired form. The construction here shown is without metal and forms a rigid and strong supporting unit.

Referring now more particularly to my invention as applied thereto, I have shown at each end of the base structure, an arched track member 12, secured between two side members 13, 13, with their upper edges extended above the top of said track member 12, as seen in Fig. 3, and all secured in the ends of the frame members 5, 5, as seen in Fig. 4.

Movably mounted upon said side members 12, to be pulled out to the position shown in Fig. 1, or pushed back to the position shown in Fig. 2, is a carrier support, composed of a frame of rectangular form and composed of the end members 14, 14, and the front and back members 15 and 16, all secured together and adapted to rest on the base frame members 5, 5, when pushed back into the divan position, as in Fig. 2. Mounted on the rearward opposite ends of this carrier support, are two rollers or wheels 17, 17,

held in any suitable manner, but to extend below the lower edges of the end frame members 14, 14, as clearly shown and so as to extend down between the side members 13, 13, and to run on the track member 12, as said carrier support is started outwardly from the position in Fig. 2, or backwardly, if out in the position seen in Fig. 1.

It will be noted that as said carrier support reaches its inward, or divan position, or its outward or bed position, that said wheels 17, 17, are free of the arched member 12, and the frame of the carrier support rests solidly upon the base frame members 5, 5. The wheels facilitate the movement of said carrier support by lifting its frame free of the base frame as said wheels run up over the arched track members 12, 12 at each end. It will be understood, however, that this carrier support could be constructed to slide out and in without the wheels, if desired, somewhat similar to a drawer.

I provide a shoulder 18 in each of the end members 13, 13, of the base, so that when said carrier support is moved outwardly to the bed position, as shown in Fig. 1, the rearward end of said carrier support will drop down in front of said shoulder 18, which will hold it against return movement inwardly until it has been tilted to free said shoulder. This is for a purpose now to be described.

Attached to the rearward edge of said carrier support is a flexible supporting member 19, which is attached at its rearward edge to a member 20, as at 21. The member 20 extends from one end of the base frame to the other end thereof and constitutes anchor means for the rearward edge of said flexible supporting member 19, as seen in Figs. 1 and 2. In Fig. 1 it is stretched outwardly, while in Fig. 2, it is collapsed in the rear of the carrier supporting frame.

Said flexible supporting member 19 can be extended from the front edge of said carrier support, if desired, as indicated, to form a covering for said support, but the rearward portion thereof forms a flexible or collapsible support for the mattress when said support is pulled out to the bed position, as shown in Fig. 1.

Mounted on said carrier support are two mattresses, 22 and 23, one on top of the other, as seen in Fig. 2. It will be noticed that with the double mattress arrangement, the seating comfort of the divan is greatly increased and that there will be no hard frame at the front edge to engage and tire the underside of the legs near the knees, but that there will be real cushion comfort. These two mattresses are here shown as hinged together at their rearward adjacent corners, by fabric 24, thus avoiding the use of metal hinges. Said mattresses are made without the usual metal springs, in keeping with one of the objects of this invention, namely, to produce a practical divan and bed without the use of any metal.

If desired, said mattresses can be provided with holding straps as 25, on the underside of mattress 23, and extended through slots 26, in said flexible supporting member 19, and attached to the lower edge of the frame member 15, as seen at 27 in Figs. 1 and 2.

Thus it will be seen that when the carrier support is pulled out from the position shown in Fig. 2 to the position shown in Fig. 1, the flexible support 19 is stretched ready to receive the back mattress and that said top mattress can

simply be turned over to the back into the position shown in Fig. 1, and will rest upon said flexible support 19, in bed position.

In order to support the outer edge of said carrier support, I have provided supporting legs, or feet, 28, pivotally attached at 29, with a shoulder 30 formed thereon to swing under the lower edge of the frame member 16, as seen in Fig. 1. There would be one of these legs at each outer corner of said carrier support. A friction block, as 31, can be used, if desired, to frictionally hold the leg up in the position shown in Fig. 2. Or the pivotal mounting can be given the required tightness to provide necessary friction for holding said leg in its raised position.

Thus I have provided a simple, practical and economical divan and bed having a rigid supporting structure, including the base, back and arms, with a carrier support movable out to bed position and a flexible supporting member positioned thereby for supporting the movable mattress, and with means for properly holding said carrier support in its out or bed position.

I do not limit my invention to the details of construction and arrangement as here shown and described for explanatory purposes, realizing that many changes in details can be made without departing from the spirit of the invention, except as I may be limited by the hereto appended claims.

I claim:

1. In a combination divan and bed structure, a supporting base having arched track members at its ends, a carrier support mounted on said base, said carrier support having wheels to run on said arched track members as said carrier support is moved from its rearward position to its forward position, the frame of said carrier support resting on said base in its divan position and in its bed-forming position, said frame being raised free of said base by said wheels moving on said arched track members to facilitate the movement of said carrier support from divan position to bed-forming position, supporting means in said base rearwardly of said carrier support when the latter is moved out to its outer bed-forming position, and double mattresses on said carrier support to move therewith, one of said mattresses being movable rearwardly upon said supporting means in said base rearwardly of said carrier support and in the same plane with the other of said mattresses.

2. In combination, a base and back and arms forming a supporting unit, said base having arched track members at its opposite sides, portions of said base extending above said arched track members to form supporting means, a carrier support mounted on said base and resting upon the portions of said base above said arched track members, said carrier support having wheels on its under side to run on said arched track members, said wheels lifting said carrier support free of the portions of said base extending above said arched track members during the greater movement of said carrier support from its rearward position to its outward position, double cushions on said carrier support to move therewith to its outward position, one of said cushions being movable rearwardly and in the same plane of the other of said cushions, and means rearwardly of the outermost cushion to support said other cushion.

SAMUEL L. GROSSMAN.
